UNITED STATES PATENT OFFICE.

JOHN ROGER OLIVER, OF MEDFIELD, MASSACHUSETTS, ASSIGNOR TO REECE SHOE MACHINERY COMPANY, OF BOSTON, MASSACHUSETTS, A CORPORATION OF MAINE.

STOPPING AND STARTING MECHANISM FOR SHOE STITCHING OR OTHER MACHINES.

Application filed April 30, 1925. Serial No. 26,948.

To all whom it may concern:

Be it known that I, JOHN ROGER OLIVER, a citizen of the United States, residing at Medfield, in the county of Norfolk, State of Massachusetts, have invented certain new and useful Improvements in Stopping and Starting Mechanism for Shoe Stitching or Other Machines, of which the following is a specification.

This invention is a novel stopping and starting mechanism for shoe stitching or other machines, and is shown applied, as an example, to the so-called outsole stitching machine, by which the outsole and welt of a shoe are stitched together, although the invention is applicable to various other types of power driven stitching machines, such as the well known button hole sewing machine, and other machines wherein it is required to bring the main or operating shaft to rest in a definite position without undue shock.

The main object of the present invention is to afford a stopping and starting mechanism which will be more efficient in the respects already mentioned and more convenient, durable and reliable in operation.

Other and more particular objects and advantages of the present invention will be explained in the hereinafter following description of one form or embodiment of the invention, or will be apparent to those skilled in the art.

To the attainment of the objects and advantages referred to the present invention consists in the novel machine, mechanism, combinations, arrangements, devices and other features herein described or illustrated.

The present invention, as to certain features, may be considered as an improvement on the mechanism shown in my prior Patent 1,532,634, granted April 7, 1925; and as the general mechanism, and its mode of use in the shoe stitching machine, may be similar to the prior patent, many details are omitted herefrom and may be ascertained by reference to the prior patent.

In the accompanying drawings, forming a part hereof, Fig. 1 is a rear elevation and central longitudinal vertical section of a mechanism embodying the present invention.

Fig. 2 is a central horizontal section of certain parts shown in Fig. 1.

Fig. 3 is a front elevation of certain parts.

Fig. 4 is a left elevation of certain parts 55 shown in Fig. 3.

Fig. 5 is a part section taken on the line 5—5 of Fig. 4.

The general object of such a stop motion may be substantially as set forth in said 60 patent, as follows: When the seam is finished or the time to stop has arrived the pedal or other control member operates to put the stopping mechanism into effect. For example when the pedal is released and rises this may unclutch the stitching shaft from the power drive and at the same time apply 65 friction to effect stoppage of the shaft. Such stoppage may be quick in point of time and without shock, but will leave the shaft 70 in an indeterminate position; and the mechanism hereof operates thereafter to turn the shaft slowly to the desired final stopping position, usually with the needle retracted 75 from the work. The slight reaction of the parts after the friction stoppage may be utilized to set into action the supplemental mechanism, for example through a latch or trigger as described in said patent. At the 80 conclusion of the final rotation the shaft will be finally stopped in the desired definite position.

The features particularly differentiating the present invention from said patent may be explained generally as follows:

In the prior patent, after the first stoppage the engagement for the supplemental slow drive was variable in time, sometimes consuming a period almost as great as a complete rotation at the slow speed before 90 the engagement thereof, owing to the possible delay in the registration of a certain clutch member or driving dog with the co-operating member on the shaft. The present invention overcomes this possible delay and renders the action quicker and more 95 uniform, namely by affording greater opportunity for the engagement of the slow driving and driven clutch members, for example by a plurality of independent driving 100 clutch dogs and associated elements co-operating with the same driven clutch member.

In the prior patent the power connections from the shaft of the machine to the slow 105 driving clutch were complicated; in the

present improvement an arrangement is provided considerably simplifying the drive and rendering it more effective and compact.

In the prior patent the final stoppage was secured at the desired point through impact members brought into relation upon throwing out the slow drive. The present improvement dispenses with all impact, and by simplified mechanism provides for final stoppage through a friction means or brake, with which it is possible to give immediate stoppage at the proper point in view of the slow speed and low momentum of the parts.

The belt 21 for the slow drive may correspond with the belt having the same reference number in the prior patent, but the connections between the belt and the drum 110 on the main stitching shaft 25 are different. In the prior patent they included pulley, shaft, helical gear, driven gear, shaft, helical gear, driven gear, shaft and pinion. In the present construction the belt 21 runs on a pulley 216, mounted on a shaft 217, journalled in a special bracket 218 located directly above the drum. The pulley and belt may be located at either end of the shaft 217, either at the front or at the rear of the machine, as indicated by Fig. 4. It is only necessary to use a worm 219 engaging a toothed worm wheel 220 on the drum 110, giving the proper speed reduction and the desired slow speed of the drum, which may be about $\frac{1}{5}$ th of the full speed of the stitching shaft.

The normal drive of the stitching shaft may be the same as in the prior patent. The foot pedal or controller operates through the fork 43, the studs 44 of which engage in groove 45 of the hub 46 of a clutch member or cone 47 rotated loosely on the stitching shaft at the full driving speed. The cooperating outer clutch cone 48 is mounted on a disk 49, the hub of which is keyed to the stitching shaft. The rim or peripheral surface 50 of the disk 49 constitutes a braking pulley and is engaged by front and rear brake straps 60 having top lugs 61 connected by a bolt 62 and lower lugs 65 connected by a bolt 74 and a spring 75, all of which may be arranged as in said patent.

The disk 49 also carries a clutch member for the slow drive in the form of an annular plate 122, having a clutch recess 123 adapted to receive a dog of the slow driving means, as will be described. Inside of the drum 110 the main shaft is surrounded by a sleeve 124 surrounded by a spring 125 accommodated in a recess in the drum and operating to press the drum toward the left, that is, toward the right in Fig. 1, tending to engage the slow drive. The spring 125 backs up against a fixed sleeve 126 supported by a bracket 127. These parts correspond in function and reference number with the prior patent. Also corresponding

with the prior patent is a follower or stud 164 arranged below the drum and adapted to rise, when released through the latch or trigger mechanism already referred to, and in due time to engage the cam groove 70 in the drum, so that the drum operates to cam itself along the main shaft after the clutching to effect the unclutching of the slow drive. As in said patent the drum 110 herein is also shown formed with a peripheral flange 129 cooperating with guards 130 and 172 at certain parts of the stopping cycle, and three buttons or projections 186, in place of the single button bearing the same number in the patent. The several elements of mechanism shown in Fig. 1 thereof below and associated with the cam follower stud 164 are indicated as identical with the prior patent and therefore are not herein described. In the prior patent the drum 110 was formed with a single cam groove, which would incur varying delays in the removing of the slow drive after the preliminary frictional stoppage of the machine. I will now describe that part of the present improvement which provides for quickening materially the engagement of the slow drive, and its subsequent disengagement.

Instead of a single slow clutch dog on drum 110 as in the prior patent the present construction indicates a plurality, namely three clutch dogs 222, and these moreover are not rigid parts of the slow rotating drum 110, but are slidable therein so that while one of them engages the single clutch recess 123 in the disk 49 the other two may yield longitudinally, this yielding moreover being made to serve a function, as will be described. Each of the three dogs is shown as having a squared front or advancing edge, but preferably a bevelled rear edge 223. Each of the dogs is in the form of a bolt or sliding bar projecting lengthwise from the drum 110 and extending through an appropriate recess in the drum, to where the inner or right hand end of the dog is formed and arranged to cooperate in the cam action. To this purpose each of the dogs has its inner end bevelled at 224 to constitute a part of one of the inclined walls of a corresponding cam groove. Also its inner end is inclined at 225, forming an upslanting surface upon which the cam follower 164 may ride out of the groove at certain times. Each of the dogs 222 is pressed outwardly to the left by spring 226 as seen in Fig. 3, tending to hold the dog in its normal or projecting position. It will be understood that each of the three dogs has the normal or operative position as seen in full lines in Figs. 3 and 5, in which it is adapted to engage with the single clutch recess 123; and each dog has also an abnormal or repressed position, in which the inner or right end of the dog takes the dotted po-

sition 227 shown in Fig. 3, in which it extends directly into the corresponding one of the cam grooves, effectually rendering that cam inoperative.

5 It will be observed that the member 110, herein termed a drum for convenience, although it might take various forms, performs various functions. It is driven slowly through the connections 216 to 220 already 10 described, and thus is a part of the supplemental or slow rotating means. It carries the clutch dogs cooperating with the recessed clutch member 122 and in that sense is a clutch member, sliding longitudinally on 15 the main shaft. It is also a controlling cam for the slow drive, cooperating with the follower or stud 164, since the engagement of the follower with the drum cam grooves causes the drum member to cam itself longitudinally for operating the clutch. The operation is assisted by the guard members 130 and 172 already mentioned, while each of the buttons 186 takes part in the operation 20 of resetting the latch mechanism, which is operated in accordance with the patent, to control the follower 164 and thereby cause the slow drive to be disengaged.

Instead of a single peripheral cam on the drum 110, as in the patent, with the possible attendant delay in engagement, the present mechanism shows the drum formed with a plurality, namely three peripheral cams 229, each one corresponding with one of the dogs 222, and the three accommodated in the periphery of the drum in an overlapping manner as indicated by Fig. 3. Each of the cams 229 commences with an inward incline or entrance portion 230, such as to let the follower 164 into the groove in a smooth and quiet manner. The first part of each cam groove is a dwell 231, which is partly bounded at the left by the right or interior end of the corresponding dog. Each cam groove thereafter takes a leftward slant 232, which also is partly bounded by the dog, namely by the bevelled end 224 of the dog. The slanting portion of the cam is followed by a second dwell 233, which terminates an elevating incline 234 adapted to throw the follower down and out in a smooth quiet manner. Associated with the inclined portion 232 of each cam groove is shown a spring guard 162. This operates to prevent sudden engagement of the follower with the inclined portion of the cam and possible shock. When the corresponding dog is thrust inwardly to its abnormal position 227 this cooperates with the guard 162, the inclined surface 225 of the dog elevating the follower and delivering it on top of the guard 162, and so rendering the cam groove inoperative.

Before describing the operation of the parts thus far enumerated the new parts constituting the final stopping means will be referred to. For this purpose the gear

220 on the drum is utilized as a flange, and its longitudinal movements transmitted to the final brake. A cross shaft 256 is shown, somewhat below the toothed drum flange 220, this shaft carrying a pair of arms 257 70 having double flanged heads 258 embracing the sides of the drum flange, as best shown in Fig. 2. Outwardly extending pins 259 on the heads 258 extend into slots 260 formed in longitudinal bars 261 projecting toward the right, in Figs. 1 and 2 toward the left, from a final stopping friction cone 262 engaging a complementary cone 263 secured to the disk 49 keyed to the main shaft. The pins 259 have a certain amount of free play 75 in the slots 260, but when thrust fully to the right they press against pins 265 sliding longitudinally in the bars 261, each of the sliding pins having a collar 266 pressed against by a spring 267 adjustable in tension by lock nuts 268. The movement of the pins 259 toward the pins 265 first applies spring pressure to the brake cone 262, and finally a positive pressure, giving sufficiently forcible friction to effect quick stoppage of 80 the slowly turning parts.

The operation may be substantially as follows: The let-up of the pedal immediately opens the friction drive clutch 47, 48, and applies the brake bands 60 to the disk 50, 95 thus promptly and smoothly stopping the shaft. During the stopping the parts are strained, and coincident with the stoppage a reaction occurs which springs the trigger described in the prior patent, thus initiating the further operations. During stitching the drum 110 is held to the right by the guard 130 as seen in Fig. 3, against the tendency of the drum spring 125 to throw the drum to the left and engage the slow drive. After 100 the first stoppage, the trigger control operates to depress the guard 130, thus releasing the drum 110, which is thereupon thrown to the left. The same movement releases the pressure of the brake band 60, 105 leaving the shaft free. When the drum is thrown to the left one of the three dogs 222 will quickly engage in the clutch recess 123. This action is almost immediate, in spite of the slow speed of the drum, because of the 110 employment of three dogs. As soon as the dog engages the recess the slow drive begins. The slow rotation of the drum is transmitted through the recessed clutch member 122 to the disk 49 and the main shaft. The two dogs that are not in driving engagement are thrust relatively to the right, to the dotted position 227 in Fig. 3, thus entering the corresponding cam grooves and rendering them inoperative as already described. The cam groove corresponding to the driving dog remains operative. The leftward movement of the drum which engages the slow drive also operates through connections 115 shown in the prior patent to release 120 the clutch dogs. The drum 110 is thus 125 driven slowly through the connections 216 to 220, the clutch dogs 222 being held in the position 227 by the pressure of the guard 130. The drum 110 is thus driven slowly through the connections 216 to 220, the clutch dogs 222 being held in the position 227 by the pressure of the guard 130. The drum 110 is thus 130

the follower 164, which is snapped upwardly by its lifting spring. If this should enter one of the inoperative cam grooves it will be thrown out by the incline 225 and guard 162. As soon as it enters the operative cam groove, corresponding with the operating dog, the cam becomes effective. The concentric cam portion 231 is not directly in line with the follower 164 in Fig. 3, but will have been moved in line with it by the leftward shift of the drum. The revolution of the drum causes the follower to travel along the dwell 231 and thence through the inclined cam portion 232, which operates to cam the drum to the right. The length of the cam incline 232 is clearly such as to throw the drum considerably beyond the normal position indicated in Fig. 3. The slow drive becomes unclutched when the follower has reached a point about midway along the cam groove 232, and thereafter the rotation of the main shaft is only by momentum, while the drum continues to be turned at slow speed by power. As the drum is thrown to its furthest right hand position its flange 220, operating through the elements shown in Fig. 2 will cause the application of the final stopping brake 262. The main shaft is thus stopped in the required final position without shock. The continued rotation of the drum restores the various parts of the mechanism to original or normal position. Thus one of the buttons 186 on the drum flange 129 operates as in the prior patent to reset the main latch or trigger. This action also throws up the guard 130 to the left of the flange 129. The guard 172 is thrown up momentarily in order to hold the drum completely to the right until the follower 164 has been elevated smoothly out of the cam slot, so as to avoid wear. Finally the follower 164 is pulled down away from the cam and latched there, the supplemental guard 172 being pulled down at the same time, permitting the flange 129 to contact the guard 130, thus restoring the parts to the position shown in Fig. 3, with everything in readiness for renewed stitching by simply depressing the pedal and engaging the main drive clutch 47, 48.

It will thus be seen that there has been described a stopping and starting mechanism embodying the principles and attaining the advantages of the present invention. Since many matters of combination, arrangement, design and detail may be modified without departing from the underlying principles it is not intended to limit the invention to such matters except so far as set forth in the appended claims.

What is claimed is:

1. In a high speed power driven machine, the combination, with a shaft thereof, of stop means operative after disconnection of

power to bring the shaft to rest without shock in an indeterminate position, and slow power means coming into action after such indeterminate stoppage for restarting and rotating the shaft slowly to a predetermined final position; said slow power means comprising a drum loosely surrounding the shaft, a clutch member thereon, a cooperating clutch member attached to the shaft, means for relatively moving said clutch members into and from engagement, a worm shaft rotated at high speed by the power source, a worm on said shaft, and a gear on said drum driven by said worm.

2. In a high speed power driven machine, the combination, with a shaft thereof, of stop means operative after disconnection of power to bring the shaft to rest without shock in an indeterminate position, slow power means coming into action after such indeterminate stoppage for restarting and rotating the shaft slowly to a predetermined final position, means for throwing out the slow speed power, and a friction brake applied to stop the slow rotating shaft at a predetermined point.

3. In a high speed power driven machine, the combination, with a shaft thereof, of stop means operative after disconnection of power to bring the shaft to rest without shock in an indeterminate position, slow power means coming into action after such indeterminate stoppage for restarting and rotating the shaft slowly to a predetermined final position, comprising a drum slideable on the shaft, power means for turning the drum, a clutch between the drum and shaft, means operative at a definite point in the shaft's rotation for shifting the drum and thereby opening said clutch, and means operated by the shifting of the drum for applying friction to cause final stoppage of the shaft.

4. The combination as in claim 3 and wherein the last mentioned means comprises a friction cone on the shaft, a complementary cone slideable longitudinally, a bar extending longitudinally and connected to operate said slideable cone, said bar having a slot, and a yielding contact therein, and a pusher moved by the drum and said slot.

5. In a high speed power driven machine, the combination, with a shaft thereof, of stop means operative after disconnection of power to bring the shaft to rest without shock in an indeterminate position, and slow power means coming into action after such indeterminate stoppage for restarting and rotating the shaft slowly to a predetermined final position, comprising a clutch member on the shaft with single shoulder, and a plurality of clutch dogs engageable therewith.

6. The combination as in claim 5 and wherein the several dogs are yieldingly

mounted so that one may engage while the others yield to inoperative positions.

7. In a high speed power driven machine, the combination, with a shaft thereof, of stop means operative after disconnection of power to bring the shaft to rest without shock in an indeterminate position, and slow power means coming into action after such indeterminate stoppage for restarting and 10 rotating the shaft slowly to a predetermined final position, comprising a drum loosely surrounding the shaft and slidably thereon, connections rotating said drum at low speed, a plurality of clutch dogs on said drum, and 15 a clutch member on the shaft engageable by any one of the clutch dogs.

8. The combination as in claim 7 and wherein the several clutch dogs are slidable in said drum, whereby all but the one making 20 clutching engagement may yield to inoperative positions.

9. The combination as in claim 7 and

wherein the drum is formed with a plurality of cams engageable with the same follower, and when so engaged adapted to cam the 25 drum in a direction to disengage the clutch.

10. The combination as in claim 7 and wherein the drum is formed with a plurality of cams engageable with the same follower, and when so engaged adapted to cam the 30 drum in a direction to disengage the clutch, and each dog arranged to slide on said drum when another of said dogs enters clutching engagement, and thereby render inoperative the corresponding cam. 35

11. The combination as in claim 7 and wherein the drum is formed with a plurality of cams engageable with the same follower, and when so engaged adapted to cam the 40 drum in a direction to disengage the clutch and apply a final stop to the shaft.

In testimony whereof, I have affixed my signature hereto.

JOHN ROGER OLIVER.
